UNITED STATES PATENT OFFICE.

JOHN A. EMBACH, OF DETROIT, MICHIGAN.

GAS ENGINE.

Application filed July 18, 1921. Serial No. 485,501.

To all whom it may concern:

Be it known that I, JOHN A. EMBACH, a citizen of the United States of America, residing at Detroit, in the county of Wayne 5 and State of Michigan, have invented certain new and useful Improvements in Gas Engines, of which the following is a specification, reference being had therein to the accompanying drawings.

10 This invention relates to a rotary internal combustion engine, and the primary object of my invention is to utilize the expansive force of detonated explosive mixtures for revolving tangentially disposed cylinders 15 about an axis eccentric relative to an annular abutment for the driven pistons within the cylinders, and by eccentrically disposing the power axis of the engine relative to the annular piston abutment, I increase the 20 power stroke of the pistons, compared to a concentric arrangement of a power axis relative to a piston abutment.

Another object of this invention is to provide a rotary internal combustion engine 25 wherein the cylinders revolve about an axis eccentrically disposed relative to piston abutments, and provision is made for constantly maintaining the abutments in a defined relation to the rotary cylinders, so that 30 the piston rods of said cylinders may be maintained in a defined relation to the cylinders to prevent unnecessary wear and tear on the pistons within the cylinders.

A further object of this invention is to 35 provide a rotary internal combustion engine wherein explosive mixtures are conducted to the cylinders and burned gases removed therefrom axially of the engine, and since the cylinders are driven about an axis 40 provision is made for safely conducting an electrical current to the spark plugs of the cylinders. As a matter of fact, the various controlling devices and accessories of the engine are disposed about the power axis 45 thereof or in proximity thereto, thus permitting of the engine being compactly constructed to occupy a comparatively small space when in use.

A still further object of this invention is 50 to furnish a rotary internal combustion engine with a timer or distributor and a rotary contact member by which circuits may be established between a magneto and the spark plugs of the engine, with the ignition properly timed relative to the intake 55

and exhaust of fuel and gases to and from the cylinders of the engine.

The above and other objects are attained by a construction that will be hereinafter described and then claimed, and reference 60 will now be had to the drawings, wherein—

Figure 1 is a side elevation of the engine partly in longitudinal section;

Fig. 2 is a plan of the engine;

Fig. 3 is a cross sectional view of the engine taken on the line III—III of Fig. 1;

Fig. 4 is a side elevation of a portion of the engine showing the timer and rotary contact member of the engine, and

Fig. 5 is a vertical cross sectional view of 70 the timer taken on the line V—V of Fig. 2.

In describing my invention by aid of the views above referred to, I desire to point out that the same are intended as merely illustrative of an engine which I have built 75 and tested, and I do not care to confine my invention to the exact construction or arrangement of parts shown, other than as confined by the appended claims.

In the drawings, the reference numeral 1 80 denotes suitable foundations for a horizontally disposed rectangular frame 2 and adjustably connected to said frame, as at 3, are bearings 4 and 5.

6 denotes a tubular or hollow driven 85 power shaft journaled in the bearings 4 and 5, and on one end of the shaft is a balance or fly wheel 7, while at the opposite end of said shaft is a fuel intake pipe 8 connected to a conventional form of carbureter 9. The pipe 8 may be secured to the bearing 5, as at 10 and the end of the shaft 6 revolves about the end of the pipe 8, thus permitting fuel to enter the hollow shaft as far as a solid or partition portion 95 11 intermediate the ends of said shaft.

12 denotes a hub fixed to the shaft 6 at the solid or partition portion 11 thereof and on said hub are radially disposed and equally spaced arms 13 supporting the inner 100 closed ends of cylinders 14 which are disposed at right angles to the arms 13 and consequently at a tangent to the shaft 6, said cylinders being supported by webs 15 connecting said cylinders, the arms 13 and 105 the hub 12.

16 denotes valve chambers at the sides of the cylinders 14, and said valve chambers are all in a common vertical plane at the intake end of the shaft 6, so that the intake 110

end 17 of each cylinder may be connected by a pipe 18 to the intake end of the shaft 6, and the exhaust end 19 of each valve chamber be connected by a pipe 20 to an exhaust manifold 21 mounted about the shaft 6. The exhaust manifold 21 communicates with a stationary exhaust pipe 22 supported about the exhaust manifold 21 by a bracket 23, carried by the bearing 5. Each valve chamber communicates with the cylinder from which it is supported, as shown by dotted lines in Fig. 3, and in each valve chamber is a spring pressed normally seated intake valve 24 and a spring pressed normally seated exhaust valve 25, these valves being preferably of the puppet type with the outer ends of the valve stems or rods exposed and adapted to be pressed when the valves are opened, either to admit fuel to the cylinders, or permit of burned gases exhausting from said cylinders.

26 denotes a cam sleeve loose on the shaft 6 and provided with three sets of cams 27 there being a set of cams for each cylinder. Engaging each set of cams are the cam rollers 28 of rods 29 and 30 slideable in brackets 31 extending outwardly from the arms 13 and the cylinders 14. The rods 29 are connected by links 32 to bell cranks or rocker arms 33 supported by some of the brackets 31 and adapted to unseat the exhaust valves 25. The rods 30 are connected by links 34 to cranks 35 of rock shafts 36, journaled in bearings 37 on the cylinders and said rock shafts have other cranks 38 adapted to unseat the intake valves 24. Each cylinder therefor has two valves with a valve operating mechanism for each valve, and one set of cams is adapted to actuate the valve operating mechanism in timed relation to the firing order of the engine.

39 denotes a gear wheel on the end of the loose cam sleeve 26, said gear wheel meshing with a small gear wheel 40 operable in unison with a gear wheel 41, the gear wheels 40 and 41 having a common hub rotatable on a stub shaft 42 supported from the bearing 4. The gear wheel 41 meshes with a gear wheel 43 fixed on the shaft 6, and this gear wheel is used for another purpose, as will hereinafter appear.

44 denotes pistons reciprocable in the outer open ends of the cylinders 14 and said pistons have piston rods 45 connected by pivoted links 46 to the arms 13, said pivoted links supporting the piston rods 45 approximately in the axes of the cylinders 14. The outer ends of the piston rods 45 are pivotally connected, as at 47, to movable piston abutments or carriages 48 having rollers or wheels 49 by which the piston abutments are movably supported in a circular tract or annular abutment supported by the frame 2. The circular track or abutment is

composed of a band or ring 50 having side brackets 51 supporting inner rails 52 which are disposed in parallelism and concentric relative to the band or outer rail 50, so that there is no chance for the movable piston abutments to become accidentally displaced when shifting about the stationary piston abutment. By reference to Fig. 1 it will be noted that the stationary or fixed annular piston abutment is in eccentric relation to the shaft 6, and this is an important feature of my invention for the reason that there will be a long power stroke for each piston starting when a cylinder is in its lowermost position and ending when the same cylinder is in its uppermost position, such taking place in the large area of the stationary abutment, at one side of the dot and dash line shown in Fig. 1, while the compression stroke of the pistons takes place in the small area of the stationary abutment, it being assumed that the cylinders are driven in the direction of the arrow shown in Fig. 1. 70 75 80 85

Since the cylinders are fixed relative to the shaft 6, the piston rods 45 supported axially of the cylinders, and the movable piston abutments or carriages 48 retained in a defined relation to the cylinders, it is apparent that the expansion of any detonated explosive mixture or gases within the cylinders will cause the cylinders to "kick back" or swing about the shaft 6 in a counterclockwise direction.

53 denotes ordinary spark plugs in the 100 valve chambers 16 for exploding any explosive mixture that may be admitted thereto when the valves 24 are open, and said spark plugs have conductors 54 extending into the hollow shaft 6 and then out of said 105 shaft to an insulator 55 provided with concentric contact rings 56, said insulator and its contact rings constituting a rotary contact member which is mounted on the shaft 6 to rotate therewith. 110

57 denotes a brush holder mounted on the bearing 4 and preferably made of insulation material, said brush holder having brushes 58 contacting with the rings 56.

energy is connected by a wire 67 to the frame 2.

68 denotes other binding posts, disposed about the binding post 65 and provided with 5 contact members 69 adapted to be successively engaged by the contact member 63. The contact posts 68 are connected by wires 70 to the brushes 58.

It is now apparent that when the contact 10 member 63 swings about the axis of the contact member 64 and the stub shaft 60 that said contact member will successively engage the contact member 69 and make and break circuits for the spark plugs 53. With 15 the gear transmission between the shaft 6 and the timer of proper ratio there will be a positive ignition system for the engine, and the gearing employed for operating the cam sleeve may be proportioned relative to 20 the timer transmission gearing so that the valve operating mechanism will be in timed relation to the firing within the engine cylinders.

The multi-cylinder engine may be used 25 for various purposes and since the revolving cylinders are confined within the annular piston abutment, the cylinders are compactly housed and the engine may be safely used without centrifugal force causing 30 stresses and strains that might dislodge parts of the engine.

In view of the fact that the rotary cylinders are disposed about a power shaft eccentric of the stationary piston abutment, 35 there is a leverage action at one side of the power shaft and consequently an increase of power, and I believe that the efficiency of the engine is the result of this eccentric relation.

40 What I claim is:—

1. A rotary internal combustion engine, comprising a power shaft, tangentially disposed cylinders carried thereby, an annular piston abutment about said cylinders, 45 movable piston abutments in said annular piston abutment, pistons in said cylinders connected to said movable piston abutment, means extending from said power shaft at one side of the plane of said cylinders permitting of explosive mixtures being admitted to said cylinders and burned gases exhausted therefrom and valvular mechanism operated by said power shaft at the other side of the plane of said cylinders for 50 controlling the admission of explosive mixtures to the cylinders and the exhaust of gases therefrom.

2. A rotary internal combustion engine

as in claim 1 and an arm supporting each cylinder relative to said power shaft, all of 60 said arms being connected to the pistons of an adjacent cylinders for maintaining said movable abutments in operative relation to said cylinders.

3. In an internal combustion engine 65 wherein cylinders containing reciprocable pistons are adapted to receive fuel to be detonated therein to cause power strokes of said pistons, valve mechanism associated with an ignition system to cause the fuel to 70 be admitted to the cylinders and burned gases exhausted from said cylinders in timed relation to the firing order of said cylinders; means whereby the pistons may have comparatively long power strokes in said cylinders, said means comprising a power shaft 75 about which the cylinders are tangentially disposed with the axes at an angle of one hundred and twenty degrees relative to each other, arms radially disposed relative to 80 said shaft supporting the closed ends of said cylinders, a movable abutment for each piston, means confining the movement of said abutments to a path in eccentric relation to said power shaft, and means connected to 85 each arm for maintaining the piston abutment of an adjacent cylinder in an operative relation thereto.

4. In an internal combustion engine 90 wherein cylinders containing reciprocable pistons are adapted to receive fuel to be detonated therein to cause power strokes of said pistons, a valve mechanism associated with an ignition system to cause the fuel to be admitted to the cylinders and burned 95 gases exhausted from said cylinders in timed relation to the firing order of said cylinders; means whereby said pistons may have comparatively long power strokes and cause 100 equally as long compression strokes, said means comprising a power shaft, arms supporting said cylinders relative to said power shaft, a stationary annular abutment in eccentric relation to said power shaft, movable abutments supported by said stationary 105 abutment, piston rods connecting said pistons to said movable abutments, and means connecting said arms and piston rods maintaining said movable abutments in operative relation to said cylinders.

In testimony whereof I affix my signature in presence of two witnesses.

JOHN A. EMBACH.
